UNITED STATES PATENT OFFICE.

FELIX KOCH, OF PITTSBURGH, PENNSYLVANIA, ASSIGNOR TO PRESSED STEEL CAR COMPANY, OF PITTSBURGH, PENNSYLVANIA, A CORPORATION OF NEW JERSEY.

CAR CONSTRUCTION.

Application filed July 13, 1923. Serial No. 651,426.

To all whom it may concern:

Be it known that I, FELIX KOCH, a citizen of the United States, residing in Pittsburgh, in the county of Allegheny and State of Pennsylvania, have invented certain new and useful Improvements in Car Construction, of which the following is a specification.

This invention relates to railway cars and more particularly to the connection of the underframe and superstructure framing of such cars and has for an object the provision of means for connecting the posts of the superstructure framing with the underframe in such a manner that in the event of an accident, the danger of the pulling of the posts away from the underframe or the shearing of the posts above the underframe will be reduced to a minimum.

Another object of the invention is to provide means whereby the posts of a railway car as well as the means for connecting the posts with the underframe may be inserted in the underframe from the upper side thereof thus facilitating the application or removal of the posts.

A further object of the invention is to provide a railway car underframe with means which, when the posts of the car are being applied, will insure the proper positioning of the lower ends of such posts.

These and other objects will be apparent from the following description.

Referring to the drawings in which like reference characters refer to like parts Fig. 1 is a plan view of an underframe of a car embodying the invention with parts cut away; Fig. 2 is a plan view of a portion of the same with the post removed; Fig. 3 is an enlarged end elevational view of the same with the post secured in its proper position; Fig. 4 is a sectional view of the same taken on the line 4—4 of Fig. 3; Fig. 5 is a sectional view taken on the line 5—5 of Fig. 1 and Fig. 6 is an end elevational view of a modification of the invention.

Referring now in detail to the drawings the reference character 1 indicates the end sill of a passenger car, which sill in the present embodiment of the invention is integral with the end portion 2 of the underframe. At each side of the longitudinal center line of the underframe a recess 3 is provided having an opening 4 preferably of I shape in plane, leading thereto from the top of the end sill for the reception of an end post 5 and gib

member 6, and having openings 7 and 8 leading into the recess from the bottom of the end sill which openings permit of the removal of cores, sand, etc. Within the recess 3 spaced ribs 9 are provided which preferably extend across the recess and from the top of the bottom thereof and assist in defining the openings 7 and 8.

Extending downwardly from the top portion of the end sill and within the recess 3 are spaced lugs 10 with which gib 11 on the members 6 are adapted to engage. Below the lugs 10 each of the ribs 9 is provided with ledges 12 having a slot 13 formed therebetween which slot tapers from its widest portion adjacent the ledges to its narrowest portion adjacent the bottom of the recess. Projecting within the openings 8 are lugs 14 on which the lower end portion of the end post 5 is adapted to rest.

Each of the end posts 5 is preferably of I form in cross section having a vertically disposed web 15 and laterally extending flanges 16 but it will be understood that this post may be of any suitable form in cross section.

Each of the gib members 6 is provided with a portion 17 adapted to be secured to the web 15 of the end post and at its lower end is provided with a gib 11 which is adapted to engage the lugs 10 within the recess 3. It will here be noted that these members 6 instead of being of the form shown in the drawings may be made of any other form so as to suit the form of end post that may be used.

To apply a post in accordance with the invention the members 6 are passed into the opening 4 and the lower portions of these members seat on the ledges 12 thus supporting the members in substantially their proper positions. The web 15 of the post 5 is then inserted between the members 6 and lowered into the opening 4 and recess 3 until the lower end portion of the post rests on the lugs 14. As the post is being lowered the web 15 will, if the post is not guided true, engage the sloping sides of the slots 13 of the ribs 9 and when in such engagement will guide the post to its proper position. When the post has been placed in its proper position the gib 11 will engage the lugs 10 while the upper portions of the members 6 are secured to the web of the post thus forming a connection between the post and the underframe possessing great strength.

In Fig. 6 a modification of the invention has been illustrated in which the end sill is provided with an upwardly extending flange to which the members 6 and the post 5 may be secured thus additionally connecting the end sill and post.

The foregoing description has been limited to end posts but it is to be understood that the invention may be used in connection with posts other than end posts and may also be used in freight car construction as well as passenger cars.

It will be apparent to those skilled in the art to which this invention appertains that changes may be made in the details of the parts forming the invention without departing from the spirit and scope of the appended claims.

Having thus described the invention what I claim as new and desire to secure by Letters Patent is:—

1. In a railway car, an underframe having a recess formed therein, a member inserted in said recess from above and having a lug for engaging said underframe within said recess, a post seated in said recess and means securing said post and member together.
2. In a railway car, an underframe having a recess formed therein, members inserted in said recess from above, lugs on said members adapted to engage said underframe within said recess, and a post seated in said recess and secured to said members.
3. In a railway car, an underframe having a recess formed therein, members inserted in said recess from above adapted to engage said underframe, and a post extending between and secured to said members.
4. In a railway car, an underframe having a recess formed therein, a lug in said recess, a post, a member secured to said post, having a projection adapted to engage said lug, said member being inserted in said recess from the top of said underframe.
5. In a railway car, an underframe having a recess formed therein, a post seated in said recess, and projections on said post adapted to engage said underframe within said recess, said projections being inserted in said recess from the upper side of said underframe.
6. In a railway car, an underframe having a recess formed therein, a post, lugs within said recess upon which said post is adapted to seat, and gib means in said recess above said lugs for connecting said underframe and post.

7. In a railway car, an underframe having a recess formed therein, lugs in said recess, a post, and gib means connected with said post, adapted to engage said lugs, said gib being inserted in said recess from the upper side of said underframe.

8. In a railway car, an underframe having a recess formed therein, a post adapted to be seated in said recess, and sloping means in said recess for guiding said post as it is moved to its seat.

9. In a railway car, an underframe having a recess formed therein, a post adapted to be inserted in said recess, and wedge shaped means in said recess for centering said post as it is inserted in said recess.

10. In a railway car, an underframe having a recess formed therein, a post adapted to be lowered into said recess, and sloping means in said recess for causing said post to automatically move to its proper position as it is lowered into said recess.

11. In a railway car, an underframe having an opening formed therein a post adapted to extend through said opening, and means below said opening for positioning said post as it is passed through said opening.

12. In a railway car, an underframe having an opening formed therein, a post in said opening, members connecting said post and underframe and passing through said opening and ledges below said members adapted to support said members.

13. In a railway car, an underframe having a recess formed therein, a rib in said recess having a slot formed therein and a post seated in said recess and occupying said slot.

14. In a railway car, an underframe having a recess formed therein, ribs in said recess and a post adapted to be received by said recess, said ribs embodying means for automatically positioning the lower end of said post.

15. In a railway car, an underframe, a post having its lower end seated in said underframe, members for connecting said post with said underframe and means for supporting said members located beneath said members.

16. In a railway car underframe having a post receiving opening and recess formed therein, and a rib in said recess having a post receiving slot formed therein, said slot being located centrally of said opening.

In testimony whereof I affix my signature.

FELIX KOCH.
